UNITED STATES PATENT OFFICE.

PHILIP BARNEY, OF TECUMSEH, ONTARIO, CANADA.

CHILD'S COT.

Application filed January 7, 1922. Serial No. 527,743.

To all whom it may concern:

Be it known that I, PHILIP BARNEY, of the town of Tecumseh, in the Province of Ontario, Canada, have invented certain new and useful Improvements in Children's Cots, of which the following is the specification.

The invention relates to improvements in children's cots and an object of the invention is to provide a cot, the sides and ends of which are severally constructed from two pieces of wire bent in a particular manner, such construction providing a cheap, durable, resilient, strong and quickly manufactured cot.

15 A further object of the invention is to construct the cot so that it can be suspended from the ends to swing and such that it can be either used as a closed cot or as a swinging seat.

20 A still further object is to construct a cot which requires no special machinery to be employed in its manufacture.

With the above more important objects in view the invention consists essentially in the arrangement and construction of parts hereinafter more particularly described and later pointed out in the appended claims, reference being had to the accompanying drawings in which:—

25 Fig. 1 is a front view of the cot.

Fig. 2 is an end view.

Fig. 3 is a plan view.

Fig. 4 is an enlarged detailed vertical sectional view through one end of the cot.

30 Fig. 5 is an enlarged detailed vertical sectional view transversely through the cot.

Fig. 6 is a perspective view showing the manner in which the sides are attached to the ends.

35 Fig. 7 is a view of the wires forming the end prior to the same being twisted to form the vertical stays.

Fig. 8 is a view of the wires forming the back prior to the same being twisted to form the vertical stays.

In the drawings like characters of reference indicate corresponding parts in the several figures.

The frame 1 of the cot is formed from an angle bar bent into a substantially rectangular shape, the horizontal flange of the bar being turned inwardly. The inturned flange of the angle bar is provided with suitably spaced holes 2 and through these holes 1 pass cross strands 3 of wire interwoven with lengthwise extending strands

4 of wire passed through the end openings. The wire strands are pulled taut so as to support a child or other person placed in the cot. The ends 5 and 6 of the cot are 60 similarly constructed, each being formed from two lengths of wire bent in the manner now described, reference being initially had to Figure 7 of the drawings.

One of the pieces of wire 7 is bent to provide what might be called two open sided squares, one square having the bottom open and the other the top. One of the ends of the wire is bent into an inverted V-shape as indicated at 8 and is looped as indicated 70 at 8' and is tied as by an end eye 9 to the body of the wire. The other of the wires 10 is bent in the same manner to provide two open sided squares but the position of the wire is reversed and neither of the ends are projected. By placing the bent wires together the open ended squares are closed and the upright portions of the wires lie in parallel pairs. I then grip the ends of the parallel upright portions and twist the intervening 80 parts together by inserting a rod or such like between them and centrally of their height and turning it. When this work is finished the end is complete and the loops 8' can be used to support the cot such as by 85 a rope, chain or such like from the ceiling.

The back 11 of the cot is formed similarly to the ends, two wires being used and each bent into open sided squares and afterwards applied on one another to form the parallel 90 vertical stay members. The ends of the stay members are gripped and the intervening portions of the vertical parallel wires are twisted in the same manner as are the cot ends. The arrangement of the wires forming 95 the back prior to twisting is shown in Figure 8 of the drawings. One end of each of the wires is bent at the top in a fanciful manner as indicated at 12 and 13 and the extremities are tied as by eyes 14 and 15 to the back. This gives the back an ornamental top. The front 16 of the cot is formed 100 from two wires initially bent and subsequently twisted in the same manner as the back of the cot. The ends of the two wires are not however extended to provide the ornamented top as indicated at 12 and 13.

The ends and back of the cot are attached to the frame 1 by wire rings 17, these rings passing through openings provided in the 110 horizontal flange of the frame and being large enough to allow of the free inward

2
folding of the ends and side when the cot is to be collapsed or crated.

The front of the cot is connected to the vertical flange of the frame by rings 18, the 5 rings being sufficiently large to allow the cot front to be folded underneath the frame. Snap hooks 19 are supplied to detachably connect the upper corners of the front, ends and back of the cot. Any convenient type 10 of snap hook will do for this cot and on this account I have not considered it necessary to detail the same.

From the above it will be obvious that this complete cot can be manufactured at 15 comparatively small cost and without requiring special tools and the complete cot is strong, yet resilient, and can be readily set up or folded as occasion requires. Further, by letting down the front one can 20 utilize the cot as a swing seat.

What I claim as my invention is:—

1. An end frame for cots formed of two pieces of wire, each shaped to provide outer and intermediate vertical members, an upper horizontal member connecting the upper extremities of the intermediate member and one of said outer members and a lower horizontal member connecting the lower extremities of the intermediate member and the remaining outer member, the two pieces thus formed being assembled by twisting the vertical members thereof together with the horizontal members of one piece opposing the horizontal members of the other piece 30 so as to form, with the vertical members, a plurality of open squares, an outer vertical member of one piece being extended upwardly above the frame thus formed and then downwardly to provide a suspension 35 loop, the free extremities of the extended portion, after forming the loop being secured to the top of the frame.

2. An end frame for cots formed of two

pieces of wire, each shaped to present outer and intermediate vertical members, an upper horizontal member connecting the intermediate and one of the outer members, a lower horizontal member connecting the intermediate and the other outer member, the upper end of the last mentioned outer member of one of the pieces being extended upwardly and bent into V form to provide a suspension loop, the free end of the extended portion being secured to the upper horizontal member of the piece, the two pieces being assembled in inverted relation by twisting the vertical members of the pieces together to provide a frame defining a plurality of open rectangular squares.

3. A side frame for cots formed of two pieces of wire, each shaped to present a plurality of vertical members and interconnecting horizontal members, the arrangement being such that each vertical member is connected at its upper end by one of the horizontal members to the corresponding end of a vertical member on one side and is connected, at its lower end, by one of the lower horizontal members, to the corresponding end of a vertical member at the opposite side, the two pieces being assembled in inverted relation by twisting the vertical members together to form a frame defining a plurality of open rectangular squares, the terminal vertical members of the two pieces being extended upwardly and horizontally above the frame to provide ornamental rails, the free extremities of such extended portions being secured to the top of the frame.

Signed at Winnipeg, this 27 day of October, 1921.

PHILIP BARNEY.

In the presence of—
GERALD S. ROXBURGH,
W. P. COONEY.
